UNITED STATES PATENT OFFICE.

JOSEPH I. VAN TOCHINE, OF FORT WAYNE, INDIANA.

DESIGN FOR A COLLAR ATTACHMENT.

44,116.

Specification for Design.

Patented May 27, 1913.

Application filed March 27, 1913. Serial No. 757,263. Term of patent 3½ years.

To all whom it may concern:

Be it known that I, JOSEPH I. VAN TOCHINE, a citizen of the United States, residing at Fort Wayne, in the county of Allen and State of Indiana, have invented a new, original, and ornamental Design for Collar Attachments, of which the following is a specification, reference being had to the accompanying drawing, forming part thereof.

The figure is a perspective view of a collar attachment, showing my new design.

I claim:

The ornamental design for a collar attachment, as shown.

JOSEPH I. VAN TOCHINE.

Witnesses:

E. EDMONSTON, Jr.,
JAMES A. KOEHL.
